UNITED STATES PATENT OFFICE

HERMAN JULIUS SCHADER, OF CHICAGO, ILLINOIS

DESIGN FOR A COMBINED LIGHTING FIXTURE AND MAIL BOX

Application filed September 19, 1931. Serial No. 41,151. Term of patent 14 years.

To all whom it may concern:

Be it known that I, HERMAN JULIUS SCHADER, a subject of Sweden, residing at 3839 Wrightwood Ave., Chicago, in the county of Cook and State of Illinois, have invented a new, original, and ornamental Design for a Combined Lighting Fixture and Mailbox, of which the following is a specification, reference being had to the accompanying drawings, forming part thereof.

Fig. 1 is a side perspective view of the design and Fig. 2 a top plan view of same.

I claim:

The ornamental design for a combined lighting fixture and mailbox, as shown.

HERMAN JULIUS SCHADER.
